Primary Examiner — Ian Simmons*Assistant Examiner* — Yolanda Robinson(74) *Attorney, Agent, or Firm* — DeLio, Peterson & Curcio LLC; Thomas E. Ciesco(57) **CLAIM**

The ornamental design for a “door lock escutcheon,” as shown and described.

DESCRIPTION

FIG. 1 is a right front top perspective view of the “door lock escutcheon” design according to our invention;

FIG. 2 is right side elevational view thereof;

FIG. 3 is a left side elevational view thereof;

FIG. 4 is a front elevational view thereof;

FIG. 5 is a rear elevational view thereof;

FIG. 6 is a top elevational view thereof; and,

FIG. 7 is a bottom elevational view thereof.

The door lock escutcheon that is shown in broken lines are for the purpose of illustrating portions that form no part of the claimed design.
